UNITED STATES PATENT OFFICE.

ALBERT E. READE, OF PETERSBURG, VIRGINIA.

ACETYLENE-GAS GENERATOR.

1,188,321.

Specification of Letters Patent. Patented June 20, 1916.

Application filed May 18, 1915. Serial No. 28,933.

To all whom it may concern:

Be it known that I, ALBERT E. READE, a citizen of the United States of America, residing at Petersburg, in the county of 5 Dinwiddie and State of Virginia, have invented certain new and useful Improvements in Acetylene-Gas Generators, of which the following is a specification, reference being had therein to the accompanying drawing.

This invention relates to an acetylene gas generator and has for its principal object the production of a simple and efficient means whereby the carbid carried thereby 15 may be immersed in a quantity of water for generating gas as the supply within the bell becomes exhausted.

Another object of this invention is the production of a simple and efficient guide 20 means for the bell which will positively retain the bell in its central position and facilitate the passing thereof into the well.

Another object of this invention is the production of a simple and efficient means 25 for retaining the carbid basket in its correct position within the bell.

With these and other objects in view, this invention consists of certain novel combinations, constructions, and arrangements of 30 parts, as will be hereinafter fully described and claimed.

In the accompanying drawing: Figure 1 is a detailed perspective view of the acetylene gas generator. Fig. 2 is a central vertical section of the acetylene gas generator. Fig. 3 is a fragmentary side elevation of the upper portion of the generator, illustrating the manner in which one of the guide rods is supported. Fig. 4 is a section taken on 35 the line 4-4 of Fig. 2. Fig. 5 is a side elevation of the carbid basket and the tube for supporting the same. Fig. 6 is a fragmentary sectional view through a slightly modified form of the invention, illustrating 40 the manner in which one of the guide rods is supported. Fig. 7 is a detailed perspective view of the lug used in supporting the rod, as disclosed in Fig. 6.

Referring to the accompanying drawing 50 by numerals 1 designates the well of the acetylene generator having the flared or funnel-like upper end 2. The bell 3 is adapted to fit within the well 1, as shown clearly in Fig. 2. This bell 3 has the ears 4 soldered upon its upper ends, the outer ends 55 of these ears being carried at a spaced dis-

tance above the bell 3 whereby the bell may pass into said well to a greater depth than would be the case if the ears were straight. The guide rods 5 extend through the apertures 6 formed in the outer ends of the ears 4 so as to guide the upper end of the bell 3 when the same moves upwardly or downwardly within the well 1. The lower ends of these guide rods 5 pass through the flared upper end of the well 1 and pass through the lugs 7 carried by means of the rivet heads 8 in engagement with the well 1. The lower ends of the guide rods 5 are held in engagement with these lugs 7 by means of 60 the solder 9 which is positioned around the lower ends of the rods 5 and upon the upper portions of the lugs 7. Therefore, while the rods 5 are held in fixed engagement with the lugs 7, they will also be braced at a spaced 65 distance from their end portions by means of the flared upper end 2 of the well 1, and in this manner the rods will be positively retained in vertical positions and in parallel 70 portions of the lugs 7. Therefore, while the rods 5 are held in fixed engagement with the lugs 7, they will also be braced at a spaced 75 distance from their end portions by means of the flared upper end 2 of the well 1, and in this manner the rods will be positively retained in vertical positions and in parallel 80 portions of the lugs 7.

The short pipe 10 extends through the upper portion of the bell 3 and has transverse openings 11 communicating with the inner portions of the bell 3. The flexible tubing 12 or short conveying pipe may be 85 passed over the upper end of the short pipe 10 so as to conduct the gas from the inner portions of the bell to any desired place. The rod 13 passes into the lower end of the short pipe 10 and this short pipe is 90 crimped into engagement with the rod so as to carry a quantity of solder 14 for fixedly retaining this rod 13 in engagement with the pipe 10. This rod extends for considerable distance below the lower end of the 95 pipe 10 and upon this rod there is detachably mounted a tube 15. The upper end of this tube 15 engages the crimped lower end of the pipe 10 and is held in a detachable position by means of the nut 16 threaded 100 into engagement with the lower end of the rod 13. A plate 17 is soldered, as shown at 18, upon the tube 15 and is provided with a cylindrical screen 19 held in fixed engagement therewith in any suitable manner, such 105 for instance as by solder, thereby forming a carbid basket. This basket is carried upon the tube, intermediate its ends and adjacent the central inner portions of the bell 3. This carbid basket is adapted to contain 110 a quantity of carbid as disclosed in Fig. 2 and therefore when the bell passes down-

wardly into the well, the carbid will be immersed in the water, as shown in Fig. 2. As a consequence, a fresh quantity of gas will be generated which will pass into the upper 5 portion of the bell and through the apertures 11 into the pipe 10 and thence to a desired place, by means of the tubing 12. If more gas is generated, the bell 3 will be raised so as to ride upon the vertical rods 5 10 until the carbid is moved completely from the water and the generation of the gas discontinued.

By referring to Figs. 6 and 7, it will be seen that the well 1 is provided with lugs 15 7' having threaded openings 20 formed therein. These lugs 7' are carried by the headed rivet 8' in a manner similar to the lug disclosed in the preferred form. The lower ends of the vertical rods 5' are threaded as shown at 21 so as to thread into the openings 20 formed in the lugs 7'. By this construction, it will be seen that the solder as shown at 9 in the preferred form may be eliminated inasmuch as the lower ends of 25 the rods 5' will be positively held against accidental displacement by passing in the lugs 7'.

From the foregoing description it will be seen that a very efficient acetylene gas generator has been produced wherein the carbid basket is carried so as to be easily immersed 30 when it is necessary to provide a fresh supply of gas, and in which the several portions are so carried as to form efficient guides 35 for each other for allowing the device to efficiently operate when necessary.

What I claim is:—

1. In an acetylene gas generator, the combination of a well, a bell reciprocally mounted within said well, a short pipe carried by and extending through the upper portions of said bell, said short pipe provided with apertures, adjacent the inner upper portions of said bell, a depending rod carried by the lower portions of said short pipe, a tube carried upon said rod, means for detachably retaining said tube upon said rod, a carbid basket fixed upon said tube, whereby when said bell moves downwardly into said well 50 carbid carried by said basket may be im-

mersed thereby generating gas, said short pipe being adapted to allow gas to escape from said bell.

2. In an acetylene gas generator, the combination of a well, a bell reciprocally mounted within said well, a short pipe carried by and extending through the upper portions of said bell, said short pipe provided with apertures adjacent the inner upper portions of said bell, said short pipe having a frusto-conical lower end, a rod extending into said frusto-conical end of said short pipe, a filler means carried within said frusto-conical end, whereby said rod will be supported, said rod having a threaded lower end, a tube positioned upon said rod, a nut removably carried by the threaded end of said rod, and engaging the lower end of said tube, whereby said tube is removably supported, and a carbid basket carried by said tube. 70

3. In an acetylene gas generator, the combination of a well, a bell reciprocally mounted within said well, a short pipe carried by and extending through the upper portions of said bell, said short pipe provided with apertures adjacent the inner portions of said bell, said short pipe having a frusto-conical lower end, a rod extending into said frusto-conical end, a filler means carried within said frusto-conical end, whereby said rod will be supported, said rod having a threaded lower end, a tube positioned upon said rod, a carbid basket carried by said tube, a nut carried upon the threaded end of said rod, whereby said tube will be removably retained upon said rod, said nut being adapted to force said tube firmly upon said frusto-conical end of said short pipe, whereby said frusto-conical end will wedge within said tube, thereby retaining said tube in a binding engagement with said nut for preventing said nut from accidentally disengaging said rod. 80 85 90

In testimony whereof I hereunto affix my signature in presence of two witnesses.

ALBERT E. READE.
